CLAIM

The ornamental design for a composite material for recordable media package assembly, as shown and described.

DESCRIPTION

FIG. 1 is a perspective view of a composite material for recordable media package assembly;
 FIG. 2 is a top elevation view of the composite material of FIG. 1;

FIG. 3 is a long side view of the composite material of FIG. 1; and,

FIG. 4 is a short side elevation view of the composite material of FIG. 1.

The broken lines shown illustrate portions of the composite material for recordable media package assembly that form no part of the claimed design.
